[57] CLAIM

The ornamental design for tailpiece for guitar, as shown and described.

DESCRIPTION

FIG. 1 is a top plan view of a tailpiece for guitar showing my new design.

FIG. 2 is a front elevational view thereof.

FIG. 3 is a left side elevational view thereof.

FIG. 4 is a right side elevational view thereof.

FIG. 5 is a bottom plan view thereof.

FIG. 6 is a rear elevational view thereof.

FIG. 7 is a reduced scale front, top and left side perspective view thereof with the broken line guitar included for illustrative purposes only and forming no part of the claimed design.
